JOSEPH C. FORSYTH, OF BROOKLYN, NEW YORK, ASSIGNOR OF ONE-FOURTH TO V. C. GILPIN AND ONE-FOURTH TO J. E. MCAULIFFE, BOTH OF BROOKLYN, NEW YORK.

ELECTRIC-LIGHT SOCKET.

1,276,634.

Specification of Letters Patent. Patented Aug. 20, 1918.

Application filed February 24, 1917. Serial No. 150,829.

To all whom it may concern:

Be it known that I, JOSEPH C. FORSYTH, a citizen of the United States, residing at Brooklyn, in the county of Kings and State 5 of New York, have invented new and useful Improvements in Electric-Light Sockets, of which the following is a specification.

This invention relates to electric light sockets or fixtures for incandescent lamps, 10 the object of the invention being to provide a socket or fixture embodying an insulating or switch box of novel construction combined with a separable head section therefor, the latter having the current wires connected thereto in such manner as to insure 15 electrical contact.

A further object in view is to provide an insulating or switch box having the parts thereof so combined that the main body of 20 the box may be detached from the head section thereof without disconnecting the current wires, thus enabling repairs to be quickly accomplished at a small cost as compared with the ordinary sockets now in use.

With the above and other objects in view, 25 the invention consists in the novel construction, combination and arrangement of parts, herein fully described, illustrated and claimed.

30 In the accompanying drawings:—

Figure 1 is a diametrical section through the removable head on the insulating box.

Fig. 2 is a diametrical section through the insulating box.

35 Fig. 3 is also a diametrical section through the insulating box taken at right angles to Fig. 2.

Fig. 4 is a bottom plan view of the removable head shown in Fig. 1.

40 Fig. 5 is a top plan view of the insulating box, with the head removed.

Referring now to the drawings, 10, designates an insulating base or box usually of porcelain, the same being formed with a chamber 11, in which is placed a metal strip 12, provided with bearing holes for the shaft or shank of a turning key 13, carrying a contact element 14, having a gap or space 15, therein. The contact member 14, 45 coöperates with a spring contact 16, for the purpose of making and breaking the circuit. One end of the strip 12, is extended through an opening 17, in the top wall of the box 10, at one side of the center thereof to form 50 a fixed plug terminal 18. Diametrically

opposite the terminal 18, is another fixed plug terminal 19, having oppositely extending arms 20, connected by fastening means 21, to the box, the means 21, being shown in the form of bolts which pass through the 60 top and bottom walls of the box. It is of course understood that these elements can be of any well known approved construction and do not have any particular relation to the invention, except in a specific manner as 65 will be referred to hereinafter.

A screw or equivalent fastening device extends centrally through the top wall of the box 10, and secures the contact strip 12, in fixed relation thereto. A bottom contact 70 strip 23, is secured within the bottom portion of the box 10, by means of a screw 23', or its equivalent.

The removable or separable head 25, is formed with a central opening 26, for the 75 lead in wires and is also formed at diametrically opposite places with sockets 27, to receive the terminals 18 and 19, above described and which project from the insulating box. In each of the sockets 27, there is 80 fastened a contact piece 28, and also arranged within each of said sockets 27, is a spring contact piece 27', or the equivalent thereof and each of said contact pieces carries a binding post 29, shown in the form of 85 a screw to which the extremities of the lead in wires are fastened as shown in Fig. 4. The head 25, is further provided with wire receiving slots 30, and arcuate lead passages 31, for the current wires, enabling the 90 extremities of the latter to be easily and securely fastened to the binding posts 29. The construction just described enables the box 10, and the head 25, to be separated to obtain access to the parts and repair the 95 latter, without disconnecting or disturbing the wires. The rotatable disk-like contact member 14, is provided with a slot 14', as shown in Fig. 3, so that it may have a movement transversely of the reduced inner portion 100 of the shank of the turn plug 18. As indicated in Figs. 2 and 3, the shank of the switch key 13, is provided with oppositely extending lugs 13', which are adapted to engage the opposing walls of the space or 105 gap 15, in the contact member 14. By the means described, the key 13, is adapted to take up and rotate the contact member 13, while at the same time a limited transverse movement of the member 14', in relation to 110

the stem of the turn plug 13, is permitted. The bolts or screws 21, not only serve to connect the sections of the box 10, together but they also secure the threaded member 5 24, to the box and form electrical connections between the arms 20, of the member 19, and said threaded member 24.

I claim:

In an electric lamp socket fixture, the 10 combination of an insulating box, terminal strips projecting from said box, one of said strips extending into the box and having oppositely disposed portions in spaced relation to each other, contact pieces arranged in 15 said box one of which is yieldable and at-

tached to the terminal strip which extends into the box, a rotatable contact member mounted between said contact pieces formed with a gap to receive a portion of the yieldable contact piece, and a turn plug for actuating said rotatable contact member having its shank journaled in bearing holes in said oppositely disposed portions of the terminal strip and passing through the rotatable contact member, said rotatable contact member 20 being movable transversely of the turn plug and the latter having a lateral projection to engage and turn said rotatable member.

In testimony whereof I affix my signature.
JOSEPH C. FORSYTH.
